UNITED STATES PATENT OFFICE

SAMUEL WILEY, OF METUCHEN, NEW JERSEY

LANDING FLARE AND RELEASING MEANS THEREFOR

Application filed July 26, 1930. Serial No. 470,976.

The present invention has reference to illuminating parachute flares adapted to be dropped from aircraft at night to illuminate terrain or water beneath the aviator, and enabling him to make a safe landing on unknown territory. The invention also relates to flares which may be used for night observation, photography and the like.

An object of the present invention is to provide an improved releasing means for carrying and releasing the flare, and which may be installed in aircraft either singly or in multiple, and either with or without a launching tube, as later herein described.

Another object of the invention is to provide a flare which is water-proof, simple in construction, positive in functioning and which may be easily installed in the releasing device and released.

At the present time, the parachute emergency landing flare falls from the releasing device by gravity, and therefore, one end of the flare casing is difficult to seal, such as the top or bottom thereof, depending upon whether the luminant drops from the bottom, or the parachute is drawn from the top of the flare, as the latter descends. It is, therefore, a purpose of this invention to improve the flare and its releasing device to overcome this difficulty.

It is a further object of the invention to provide a flare of improved construction, and a supporting and releasing means therefor, which is of an improved construction to cooperate with the flare, so that the flare may be sealed at top and bottom, and when placed in the releasing device, is automatically partially opened, and when released is completely opened by its action of falling, so as to insure exposing the parachute to the action of the air, and consequently insure the proper support and setting off of the flare.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of a flare mounted and latched in a releasing device, the flare and releasing device being constructed according to the present invention.

Figure 2 is an enlarged top plan view of the same.

Figure 3 is a detail perspective view of the flare cap and its sliding support.

Figure 4 is a vertical section taken centrally through the flare and its releasing device, the section being taken axially at right angles to the showing in Figure 1.

Figure 5 is a transverse section taken through the intermediate portion of the flare on the line 5—5 of Figure 4, the view being enlarged.

Figure 6 is a side elevation, partly in section, of the flare immediately after the same has been released completely from the releasing device and the flare cap.

Figure 7 is a similar view showing a flare mounted on the sliding carrier and about to be moved up into the releasing device.

Figure 8 is a top plan view of a flare connected to the releasing device, showing a modification in the supporting slide means.

Figure 9 is a fragmentary side elevation of the same.

Figure 10 is a detail perspective view of the slide for the flare cap.

Figure 11 is a side elevation of the release guide, showing the lower end of the same and a cap in its lowermost position subsequent to the release of the flare.

Figure 12 is a detail perspective view of one of the cap holders carried on the lower end of the releasing guide.

Figure 13 is a fragmentary side elevation of a modified form of releasing device and flare for cooperation therewith.

Figure 14 is a transverse section taken through the upper end portion of the same on the line 14—14 of Figure 13.

Figure 15 is a detail transverse section, enlarged, taken through the cap and the supporting means therefor, on the line 15—15 of Figure 14.

Figure 16 is a detail perspective view showing the combined cap turning and latch releasing levers.

Figure 17 is a side elevation, partly in section, of a multiple release device showing means for consecutively releasing flares one at a time.

Figure 18 is a top plan view of the same.

Figure 19 is a detail perspective view of one of the cap stops disposed in relation to the cap projection, and

Figure 20 is a detail perspective view of the slide bar for releasing the flares from the multiple holder of Figure 17.

Referring now to the drawings, and first to the form of the invention disclosed in Figures 1 to 5, 25 designates the casing of the flare which is of combustible material and contains an illuminating composition. The casing 25 contains the luminant of the flare and is surmounted by a parachute casing 26 of any suitable material, preferably light sheet metal, and which at its lower end embraces and is secured by nails, screws, or the like, to the upper end of the combustible casing 25. The upper and lower compartments of the flare are separated by a horizontal partition 27 in the form of a wood block, or other suitable material or device. As shown particularly in Figure 4, the wood block 27 is hollowed out at its upper side to provide a depressed chamber in its upper face, and is likewise hollowed out in its lower side to provide a lower chamber. The intermediate portion of the block 27 is apertured and is rabbed at its under side about the aperture to provide a seating flange 28, against which is seated an igniter in the form of a block of wood 29, or the like. The igniter 29 is provided with a length of friction wire 30 having its ends extending downwardly through the igniter 29, and which may comprise a plurality of strands twisted or braided together, and with the strands intermediate the ends of the wire 30 separated for the reception of the shank of a screw 31, which is carried in the upper depressed side of the block 29. A thin disk 32 of soft aluminum, or other suitable material, is held in place by a paper or fiber washer 33 for the purpose of placing tension on the friction wire 30.

The ends of the friction wire 30 pass through friction primers 34, which are mounted in the block 29. The screw 31 extends upwardly through the friction wire 30 and the disks 32 and 33, and engages the intermediate portion of a U-shaped clip 35, the upstanding arms of which are apertured for the reception of one strand or length of the suspension cable 36 which leads to the parachute. The lower ends of the cable 36 may be attached to the flare in any suitable manner, but preferably by passing the lower free ends of the cable 36 through openings in the partition block 27, knotting the lower extremities of the cable ends and seating the same with lead or the like in countersinks in the lower side of the partition 27, as clearly

shown in Figure 4. The clip 35 is engaged with an intermediate portion of the cable 36, so that when the clip 35 is taken up by the upper portion of the cable, there is still considerable slack in the lower portion of the cable, so that the weight of the flare is imposed directly upon the clip 35 and the parts connected thereto for quickly dislodging said parts from the partition block 27, and drawing the friction wire 30 through the primers 34 to set off the flare. The central portion of the luminant casing 25 is provided with a flash tube 37 of any suitable diameter and construction, and which extends centrally therethrough, and in which is placed a quickmatch 38, which leads from the lower compartment of the partition 27 to the underside of the body of illuminating material, so that the body of illuminating material is lighted only at its lower end, and is adapted to first blow or burn out the easily removable bottom 39 for normally protecting the luminant by closing the lower end of the casing 25.

The flare thus constructed is provided preferably opposite the partition block 27 with an overturned or downwardly directed hook 40 disposed at one side of the flare. The hook 40 is provided with a shank portion 41 of reduced width, as clearly shown in Figures 4 and 5, the hook 40 outstanding from the side of the flare for a purpose which will hereinafter appear.

Disposed in the upper casing or compartment 26 is a parachute 42 of any suitable construction, which is provided with shrouds 43 connected at their lower ends to the upper end portion of the suspension cable 36. The upper parachute casing 26 is provided with a cap 44 which is constructed of the desired suitable depth, and which has its depending wall or flange arranged to overlap the upper end portion of the casing 26, and which is detachably interlocked therewith by corresponding depressions or projections 45 on the cap and the casing, and which are disposed in the manner of a bayonet slot or pin for holding the cap 44 firmly upon the upper end of the flare when the cap is turned on the flare into a full locking position. The cap 44 is provided on its top with an upwardly offset strap or handle 46, by means of which the flare may be manipulated in packing, unpacking and adjusting the same for application to the airplane. The strap 46 is adapted to receive therein the horizontal shank 47 of a sliding support or shoe 48. The shank 47 is preferably flat and hollow and adapted to engage through the opening or slot provided beneath the intermediate upset portion of the strap handle 46.

The hollow shank 47 is provided with a spring tongue 49 which is secured at its inner end by means of bolts and nuts 50 to the upper wall of the shank 47, and at its outer

end carries a locking dog 51, which is provided at its outer end and side with a bevel or cam face adapted to engage against one edge of the handle 46, as the flare is pressed inwardly toward the inner end of the shank

5 47. As soon as the dog 51 escapes past the outer edge of the handle 46, the spring tongue 49 snaps the dog 51 upwardly into position at the edge of the strap 46, so as to hold the shank 47 from being withdrawn through the handle. The tongue 49 extends beyond the end of the shank 47 and provides a lip 52, which will be depressed by the thumb or finger for retracting the dog 51 out of the path of the handle 46, so that the cap of the flare 10 may be quickly and easily removed from the sliding support 48.

As is best shown in Figure 3, the sliding support 48 may comprise a flat plate which is turned upwardly from the inner end of the shank 47 and which is provided near its upper end and at its lateral edges with a pair of relatively narrow tongues or arms 53 shaped and so disposed relatively to each other as to embrace the opposite outer faces of a pair of outwardly flaring vertically disposed guide flanges 54. The flanges 54 are on the channel body 55 of the releasing device. The channel shaped body is vertically disposed and provided at its upper and lower ends with brackets 56 of any suitable construction and configuration adapted for attachment to aircraft for holding the channel member 55 in substantially vertical position.

35 The lower end of the channel member 55 is provided with a pair of stops 57, which may be in the form of angle irons, as shown in Figure 1, secured to the opposite sides of the channel member 55, and extending across the lower ends thereof to provide abutments against which the tongues 53 are adapted to strike when the sliding support moves downward into its lowermost position. These stops 57 are adapted to engage the cover carrier and suddenly arrest the downward travel of the cover, so that the body portion of the flare will be separated from the cover merely by the force of inertia when the travel of the cover is suddenly arrested.

50 When the flare is first raised into the releasing device, the cap 44 is primarily or initially released to some extent from the upper end of the flare body. To accomplish this, the channel member 55 is provided in its lower end portion, and intermediate the wings 54, with a vertical slot 58 of sufficient size to receive the neck portion 41 of the hook 40, and the lateral marginal edges of the slots 58 and the lower end of the latter are bevelled and flare downwardly. These flared edges of the slot 58 provide a downwardly flaring mouth adapted to receive the neck 41 of the hook, and deflect the hook 55 into true alignment with the slot 58 as the

flare is forced upwardly. The hook 40, therefore, turns the body of the flare as the latter is moved upwardly into the releasing device, where the cap 44 is carried by the shank 47 and held against turning.

70 The result is that the units of the bayonet slots will be operated to some degree, such as shown in dotted lines in Figure 1, the bayonet slot elements being so proportioned and arranged as to effect an initial upward movement of the cap 44 on the body portion of the flare as the latter turns within and beneath the cap.

75 For the purpose of holding the flare, with its cap, in raised set position in the releasing device, a pivoted latch 59, mounted on a pivot 60 on the back or outer side of the channel member 55, is provided with a downwardly extending and edgewise offset hook 61 proportioned to engage beneath the shank 41 of the hook 40 and support the flare by the interlocking engagement of the hooks 40 and 61. The hook 61 has a lower bevelled face adapted to be engaged by the shank portion 41 of the flare hook for swinging the latch hook 61 to one side during the upward movement of the hook 40 into its normal set position. The latch lever 59 is urged to turn into locking position by a spring 62 and is maintained in a normal set position 80 by a stop pin 63, as shown in Figure 1. A releasing cord 64 is connected to the upper end of the latch 59 and is adapted to be drawn against the tension of the spring 62 for swinging the latch 59 and releasing the hook 61 thereof from the flare hook 40.

85 The operation of this preferred form of the invention is as follows:—

90 In Figure 7, the sliding support 48 is in its lowermost position, such as it assumes after a flare has been discharged, and the cap of the discharged flare has been removed from the shank 47. A new flare is thus engaged by its strap 46 with the shank 47, and then the flare is grasped by its lower end and 95 pushed upwardly, the sliding support 48 moving upwardly on the wings 54 of the guide channel strip 55. During this upward movement, the flare hook 40 is offset angularly with respect to the axis of the flare, 100 and with respect to the transverse position of the strap 46 and the shank 47, so that, as shown by the central axial line in Figure 7, the hook 40 is offset under one side with respect to the guide slot 58 of the channel member 55. However, as the flare reaches its uppermost position, the shank 41 of the hook engages the bevelled edges of the slot 58, and the body portion of the flare is turned on its axis and within the cap 44 from 105 substantially the position shown in Figure 7 to the position shown in Figure 1. The cap 44 is held against turning as it is interlocked with the sliding carrier 48, and thus the elements of the bayonet slot connections be- 110

115

120

125

130

tween the flare body and the flare cap are released to such extent that the cap is readily removed by a direct relatively longitudinal movement between the cap and the flare body.

5 As the flare body is thus forced up into position and turned to release the bayonet slot locks of the cap, the hook 40 also performs the function of retracting the latch lever 59 and of finally interlocking with the hook 61 thereof, and thus securely hold the flare in raised position and with the cover partly released.

When it is desired to release the flare, the 15 aviator draws the release cord 64 a distance sufficient to swing the hook 61 from beneath the flare hook 40, so that the body of the flare and the cap are simultaneously released, the cap and flare body falling downwardly 20 with the hook 40 sliding in the slot 58, and the support 48 connected to the cap sliding on the wing flanges 54. The flare, with its cap, gains momentum as it falls, and when the sliding support 48 reaches the lower end of 25 the guide channel 55, the tongues 53 of the sliding support engage the stops 57, and thus bring the sliding support 48 suddenly to a stop. The momentum of the body portion of the flare, together with its weight, is more than sufficient to pull the upper end of the 30 casing 26 out of the cap 44, so that the parachute compartment is open, and as the cap 44 may have considerable depth, the upper end of the parachute is exposed, so that the 35 air has easy access thereto for opening the parachute and drawing the shrouds 43 and the suspension cable 36 taut.

As the cable 36 is drawn taut, and before 40 it takes up the weight of the flare, the cable pulls the clip 35 out of its seat in the fuse block 29, breaking the adjacent paper seals, and the like, and drawing the friction wire 30 through the primers 34 to produce the desired spark for igniting the quickmatch 38, which leads down through the tube 37. The 45 flare, being thus ignited, the suspension cable 36 is still further drawn to taut position, so as to suspend the flare from the partition block 27, which is secured in the upper end of the luminant casing 25.

50 Figure 6 shows the flare body immediately subsequent to its release from the stopped cap 44, and wherein the parachute is acted on by the air and is partly withdrawn from its casing 26. The cap 44 is now removed from the horizontal shank 47 by depressing the spring tongue 52 and depressing the dog 51 out of engagement with the handle 46. The 55 next flare is mounted on the shank 47 by merely sliding the handle 46 of the flare over the shank into the position shown in Figures 4 and 7. The operation is now repeated with respect to the new flare.

With reference to the modification shown 60 in Figures 8 to 12, both inclusive, the flare cap

44 is provided across its top with a strap handle 65 of any suitable configuration to facilitate the handling and transportation of the flare.

Projecting from one end of the handle 65 70 is a stop projection 66 for a purpose which will hereinafter appear, and from the opposite end of the handle 65, there projects from the cap 44 a supporting plate 67, which is riveted or otherwise suitably secured in flat 75 relation on the upper side of the cap 44, and with one edge portion of the plate projecting considerably beyond the adjacent side of the cap. The projecting edge portion of the plate 67 is recessed and provided with inwardly 80 diverging slots 68 providing passages or ways adapted to receive the wings 54 of the vertical guide channel 55 forming the frame or body part of the releasing mechanism. The plate 67 is, therefore, maintained in horizontal 85 position at right angles to the guide channel 55, so as to hold the cap 44 in outstanding substantially horizontal relation to the guide channel. The supporting plate 67 is provided, outwardly of the slots 68, with spaced 90 downturned fingers 69, which lie at opposite sides of the channel rail 55, and which are adapted to align with and be received in hook sockets 70 which, as shown in Figures 9 and 12 particularly, are riveted or otherwise suitably secured to the lower ends of the 95 channel rail 55. As the plate 67 is riveted or otherwise permanently secured to the cap 44, it is necessary to remove the plate 67, with the cap 44, from the releasing device after 100 each discharge of a flare. For this reason, the wings 54 are cut away to provide slots 71 at their lower ends, and immediately above the socket hooks 70, so that after the flare body has left the cap 44, the cap may be grasped in 10 the hand and easily raised into position for releasing the fingers 69 from the hooks 70, and then draw the plate 67 forwardly and outwardly from the vertical guide rail.

Referring now to the modification shown 11 in Figures 13 to 16, the cap 44 may be of the construction disclosed in Figure 1, and provided with a strap handle 46 adapted to receive the shank 47 of the vertically sliding support 48. The support 48 is slidably 11 mounted on the vertical channel rail 55, and engages the wings 54 thereof, as above set forth. The cap 44 is provided at one side with a substantially radially extending lug or projection 72 adapted to lie beneath the 12 shank 47, when the flare cap is mounted on the shank, and which also projects toward the channel rail 55. The present modification embodies means engaging the lug 72 for turning the cap 44, while the hook 40 holds the 13 body portion of the flare from turning, so as to release or unlock the bayonet joints between the cap and the flare body. To this end, the channel rail 55 has at its outer side a latch lever 73 pivoted at 74 in a manner simi- 14

lar to the mounting of the latch lever 59. The latch lever 73 carries at its lower end the hook 61 to interlock, as above described, with the hook 40. A spring 75 engages the latch lever 73 at a point below the pivot 74, and the latch lever is provided with a tail piece 76 which extends upwardly from the pivot 74 and lies closely adjacent to one side of a cap turning lever 77. The lever 77 is pivotally mounted 10 at its lower end on the pivot 74, and is provided at its rear edge with a laterally turned projection 78, which registers with the rear edge of the tail piece 76, so that when the lever 77 is swung forwardly through a predetermined distance, the overturned lug 78 will 15 then take against the tail piece 77 and impart any continued movement of the lever 77 to the latch 73.

The lever 77 is apertured at its upper end 20 for the reception of the end of a combined cap unlocking and flare release cord 79. The lever 77 is also provided near its upper and at its forward edge with an inwardly extending projection 80 lying in the path of the lug 25 72 of the cap 44, so that the forward swinging of the lever 77 brings the projection 80 into contact with the lug 72 and moves the lug laterally of the guide channel 55, and thus turns the cap 44 on the body of the flare, so 30 as to partly release the cap, or at least unlock it from the bayonet slot, or other device which may be used. The lever 77 may be provided with a separate spring 81 for normally returning the lever 77 into position out 35 of engagement with the latch lever 73, and so as to clear the lug 72 and admit of the upward sliding movement of a new flare into position after the discharge and removal of the first flare.

40 The cap 44 is turned with respect to the sliding support 48 and its shank 47, held fixed to the wings 54. The shank 47 is relatively narrow as compared with the width of the upwardly offset handle 46, so that the cap, 45 with the handle 46 secured thereto, may rock or swing freely to a limited extent, but with sufficient amplitude to release the bayonet slot, or other interlocking means, between the cap and the flare body.

50 With reference now to Figures 17 and 18, there is shown an embodiment of the invention adapted to support and release, in a desired manner, two or more flares. For the purpose of convenience in explanation and illustration, the device is disclosed as adapted for individual, intermittent and consecutive delivery of three flares. Of course, any desired number of flares may be used, and they may be grouped in any desired manner. 55 The casing 82 is divided by partitions 83 into three vertical compartments open at their lower ends. Each compartment is provided with the vertical channel strip 55, and its accompanying parts, such as shown in 60 Figure 1. The latch levers 59, however, are

not directly connected to a release cord, but are provided at their upper ends with forwardly bevelled projections 84, which also have rearwardly facing shoulders. A releasing bar 85 is arranged horizontally across 70 the upper ends of the latch levers 59, and is slidably supported on fixed pins 86 suitably mounted on the casing 82, and which engage through slots 87 arranged in the opposite end portions of the releasing bar 85. The releasing bar 85 is provided with a pendant sear 88 for each latch lever 59, and the sears 88 are arranged in consecutively increasing distances apart from the lugs or projections 84 of the latch levers 59 to insure the tripping of 80 the preceding latch lever prior to the movement of the succeeding sear 88 into position to operate the next latch lever 59. The releasing bar 85 is connected at its rear end to a return cord 89 adapted to draw the bar 85 rearwardly into an initial position determined by the engagement of the pins 86 in the forward ends of the slots 87.

85 Each sear 88 has a stop pin 90 arranged to engage the rear edge thereof for holding the sear 88 against swinging backwardly from the projection 84 when the releasing bar 85 is moved in a forward direction. It will be noted that the sears 88 have rearwardly bevelled lower ends adapted to cooperate with 90 the forwardly bevelled upper ends of the lugs 84 for tripping the sears 88 over the projections 84, as the releasing bar 85 is returned to 95 normal position.

100 The releasing bar 85 is provided in its upper edge with a plurality of teeth or shoulders 91, one tooth or shoulder for each latch bar 59 employed. A slide bar 92, shown in detail in Figure 20, is mounted over the releasing bar 85. The slide bar 92 is preferably of channel construction and carries intermediate its ends a dog 93 normally urged downwardly at its free end by a spring 94 for interlocking the dog with one of the teeth 91. The slide bar 92 has at each end longitudinal slots 95, 105 through which engage fixed supporting pins 96. The slots 95 are of such length as to permit of the longitudinal movement of the slide bar 92 a distance equal to the advancement of the releasing bar 85 sufficiently to release one 110 latch bar 59. This insures that but one flare at a time will be released, and upon each pull on the release cord 97, which is attached to the forward end of the slide bar 92. A spring 98 is connected at one end in fixed relation in 115 the casing 82, and at its other end is attached to the rear end of the slide bar 92 for drawing the same backwardly into normal position of rest against the stop pins 96.

120 It is apparent that when the release cord 97 is drawn forwardly, the slide bar 92 moves therewith against the tension of spring 98, and the dog 93 engages the first tooth 91 and pulls the releasing bar 85 along with the slide bar until the pins 96 arrest the motion of both 125 130

of the bars. During this first movement of the bar 92, the first sear 88 trips the first latch lever 59 and releases the first flare. The releasing bar 85 remains in this position while the spring 98 returns the slide bar 92 to its normal position, and the dog 93 slides over the second tooth and interlocks therewith.

The second time the release cord 97 is pulled, the slide bar 92 again advances within the limit of its slots 95 and steps the releasing bar 85 forwardly another distance sufficient to move the second sear 88 to trip the second latch lever 59 and bring the third sear into position adjacent the shoulder of the third projection 84. The releasing bar 85 remains in advanced position each time, so that it is gradually stepped forward to bring the sears 88 first into position to operate and adjacent latch lever 59, and then to operate the same. After all of the flares have been discharged from the casing 82, the cord 89 is then pulled to return the releasing bar 85 to its original position, and all of the sears 88 freely trip over the upper ends of the projections 84. A cord 99 is provided for the dog 93 to raise the same and admit the return of the teeth 91 with their bar 85 to normal position.

Another feature, which is disclosed in connection with the multiple or gang release, is the provision in the lower end of the casing 82, and in each compartment thereof, with the pivoted stop lever 99 pivoted near one end on a pivot 100, and resting at its outer end on a stop 101. The heel or inner end of the lever 99 is connected to a spring 102 suitably mounted in the casing 82 for normally holding the free end of the stop lever 99 downwardly on its rest 101. Each stop lever is arranged diametrically opposite to the stops 57 on the lower end of the vertical channel rail 55. The stop lever 99 is adapted to yield against upward pressure of the outwardly extending stop lugs 66, shown in Figure 8, on the remote side of the cap or cover 44 so that the cap or cover will be supported in like manner in opposite sides of the compartment, as the flare moves downwardly and is discharged from the releasing device.

To protect the flare when in the launching device, the lower end of each compartment in the casing 82 may be provided with a dust cap 104 of light material. The dust cap 104 may be of disk form and conforms in shape to the cross sectional configuration of the compartment and provided with a downturned marginal flange seating against the inner walls of the compartment and seating the cap 104 therein. Bendable tongues 105 are carried on the lower edges of the flanges of the cap 104 and are bent or rolled outwardly and upwardly over lugs 106 to yieldably hold the caps 104 in place.

The weight of the flare is adapted to force the cap 104 out of the lower end of the compartment when the flare is released. The

caps 104 prevent entry of dust, water and the like up into the casing 82, and thus protect the flares when adjusted in the launching device.

It will be obvious that various changes in the construction, combination and arrangement of the parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. An illuminating parachute flare, comprising an illuminant casing, a parachute casing connected thereto, a parachute mounted in the parachute casing, igniter means carried in the lower casing connected to the parachute for setting off the flare and the parachute having connection with said illuminant casing for supporting the same, a cap detachably interlocked upon the upper end of the parachute casing, releasable supporting means for receiving the casings by axial turning thereof, and cap retaining means between the cap and the releasable supporting means to hold the cap from turning for initially unlocking the cap upon the positioning of the flare on said supporting means.

2. An illuminating parachute flare, comprising upper and lower casings, a parachute mounted in the upper casing and connected to the lower casing, a cap interlocked by relative rotary movement upon the upper end of the upper casing, supporting means for the flare, cooperating means between the supporting means the upper casing and the cap for relatively turning the upper casing and the cap to initially release the cap upon the positioning of the flare upon the supporting means, and stop means for engaging the cap upon a predetermined downward movement of the flare when released to completely remove the cap from the casing.

3. An illuminating parachute flare, comprising a luminant casing and a parachute casing connected thereto, an igniter carried in the luminant casing, a parachute mounted in the parachute casing and connected to the igniter to operate the same upon the initial opening of the parachute and connected to the luminant casing for supporting the same upon the complete opening of the parachute, a cap for the parachute casing, a vertical guide engaging the parachute casing, a movable support engaging said guide and connected to the cap, means between said guide and parachute casing and between the support, and the cap for relatively turning the same and initially unlocking the cap from the parachute casing upon the positioning of the latter in the guide, and releasable means for holding the parachute casing and the cap support in raised position.

4. An illuminating parachute flare, com-

prising a luminant casing having a hook on one side, a parachute casing connected to the upper end of the luminant casing and open at its upper end, a parachute in the parachute casing connected to the luminant casing, a cap on the upper end of the parachute casing, means operable upon the relative rotation of the cap and casing for releasing the cap from the casing, a vertical supporting guide having a vertical way therein adapted to receive said hook to hold the casing from turning during upward movement on the vertical guide, a slidable support mounted on the guide and engaging said cap to hold the same in relative position with respect to the guide, said support and said way being disposed in relatively angular relation for relatively turning the cap on the casing upon the upward movement of the flare on said vertical support, and latching means carried by the vertical support for engaging the hook on the casing to support the same in the guide.

5. An illuminating parachute flare, comprising a double casing, a luminant composition disposed in the lower portion of the casing, a parachute mounted in the upper portion of the casing and connected to the lower portion thereof, a cap on the upper portion of the casing, said casing and cap having interlocking parts adapted for engagement upon the relative turning of the cap and casing, a vertical guide for the cap casing, and means between the vertical guide and the casing for effecting the relative turning of the casing upon the upward movement of the flare on the guide, and means between the guide and the cap to hold the latter from turning to initially unlock the cap.

6. An illuminating parachute flare, comprising a casing having a parachute compartment in its upper end, a parachute mounted in said compartment and connected to the casing, a cap closing the casing, interlocking means between the cap and casing for engagement upon the relative turning of the cap and casing, a vertical guide for the cap and casing, a latch for engagement with said casing to hold the casing and the cap in raised position, releasing means for said latch arranged between the same and said cap for initially turning the cap into unlocked position and subsequently releasing said casing, whereby the casing and cap are permitted to fall, and means lying in the path of the cap for arresting the downward movement thereof to free the cap from the casing after a predetermined downward movement of the same.

7. In combination with a flare having a case with a cover, a launching tube for the flare, a releasing device on the tube for freeing the flare, retaining means on the tube for engagement with said cover for retaining the same when the flare case leaves the

tube, said cover retaining means being yieldable upon the upward movement of the flare into position in the launching tube, a protecting cap on the lower end of the tube to enclose the flare therein, and releasable means 70 for holding the cap in place.

8. In combination with a flare, a launching tube therefor, means for releasably supporting the flare in the tube, a closure cap, and releasable means for holding the cap on the lower end of the tube to enclose the flare therein, said releasable holding means adapted to yield under weight of the flare when released, whereby downward movement of the flare is adapted to remove the cap from the tube and 80 open the latter.

9. In combination with a casing having a plurality of flare receiving compartments, a flare for each compartment and having a laterally extending hook, a latch lever for each compartment adapted to engage the hook of the respective flare for supporting the latter in its compartment, a releasing bar slidably arranged across said latch levers, abutting means spaced along said releasing 90 bar at consecutively increasing distances from the respective latch levers, a reciprocating member, and means between the reciprocating member and the releasing bar for advancing the releasing bar in successive steps 95 upon the repeated operation of the reciprocating member for actuating said latch levers one at a time and in successive order.
